(57) **CLAIM**

The ornamental design for a model vehicle steering bellcrank cap as shown and described.

DESCRIPTION

FIG. 1 is an upper, left, rear perspective view of a model vehicle steering bellcrank cap showing our new design;

FIG. 2 is a lower, left, front perspective view thereof;

FIG. 3 is a front elevation view thereof; the rear, left, and

right elevation views are a mirror image thereto;

FIG. 4 is an upper plan view thereof; and,

FIG. 5 is a lower plan view of the model vehicle steering bellcrank cap.

In the drawings, the broken lines illustrate portions of the model vehicle steering bellcrank cap that form no part of the claimed design.
